(57) **CLAIM**

The ornamental design for an air intake manifold, as shown and described.

DESCRIPTION

FIG. 1 is a perspective top view for an air intake manifold showing my new design;

FIG. 2 is a perspective bottom view thereof;

FIG. 3 is a top view thereof;

FIG. 4 is a right side view thereof;

FIG. 5 is a bottom view thereof;

FIG. 6 is a left side view thereof;

FIG. 7 is a front view thereof; and,

FIG. 8 is a back view thereof.

The broken line showing portions of an air intake manifold is included for the purpose of illustrating environmental structure and forms no part of the claimed design.

1 Claim, 5 Drawing Sheets
